UNITED STATES PATENT OFFICE.

HARRY W. ALLISON, OF EAST LIVERPOOL, OHIO, ASSIGNOR TO W. T. ROBERTS, OF EAST LIVERPOOL, OHIO.

WRENCH.

No. 899,197.

Specification of Letters Patent.

Patented Sept. 22, 1908.

Application filed December 20, 1906. Serial No. 348,803.

To all whom it may concern:

Be it known that I, HARRY W. ALLISON, citizen of the United States of America, residing at East Liverpool, in the county of Columbiana and State of Ohio, have invented 5 certain new and useful Improvements in Wrenches, of which the following is a specification, reference being had therein to the accompanying drawing.

10 This invention relates to wrenches, and the invention has for its object to provide a wrench of simple and durable construction that can be easily and quickly manipulated to grip a pipe, nut or similar article.

15 Another object of this invention is to dispense with the use of screw threads, springs and other delicate mechanism used in connection with wrenches.

To this end, I have devised a wrench consisting of practically three parts, two pivotally connected jaws and a handle or lever having a segmental slot extending at an angle to the longitudinal plane of the handle, one of the jaws being pivoted to the handle 25 or lever while the other of said jaws is movably connected at one end to the handle or lever. The jaws are opened and closed by placing one of said jaws in engagement with an object and then manipulating the handle 30 or lever, the distance between the pivotal points of the jaws varying, whereby one of said jaws travels in a path not described by the other of said jaws.

The detail construction of my improved 35 wrench will be presently described and then specifically pointed out in the appended claims, and referring to the drawing forming part of this specification, like numerals of reference designate corresponding parts throughout the several views, in which:—

Figure 1 is a view from one edge of the improved wrench, Fig. 2 is a side elevation of the wrench illustrating the jaws in three different positions, Fig. 3 is a view of the opposite site edge of the improved wrench from that illustrated in Fig. 1, Fig. 4 is a perspective view of the one end portion of the handle or lever, Fig. 5 is a perspective view of one of the jaws of the wrench, Fig. 6 is a similar 50 view of the other jaw.

To put my invention into practice, I construct my improved wrench of two jaws 1 and 2, and a handle or lever 3. The jaw 1 (see Fig. 6) has one end bifurcated and 55 pierced, as at 4, while its opposite end is cut

away as at 5 and provided with a threaded opening 6. The jaw intermediate its ends is formed with an enlarged bifurcated portion 7 having transverse openings 8 formed therein. The jaw 2 has its one end bifurcated and pierced, as at 9, while its opposite end is cut away, as at 10, with the cut away portion recessed as at 11 and provided with a threaded opening 12 leading from the bottom of the recess. The jaw 2 intermediate its ends is provided with a web portion 14 having an opening 15 formed therein. The handle or lever 3 has a segment-shaped end 16, which is provided with a segment-shaped slot 17 and an opening 18, the slot 17 extending at an angle to the longitudinal plane of the handle. The web portion 14 of the jaw 2 is pivotally mounted in the intermediate bifurcated enlargement 7 of the jaw 1, by a pin or rivet 19, thus connecting the two jaws 75 together, whereby the cut away ends of said jaws can be brought into close proximity to one another. The bifurcated and pierced end 4 of the jaw 1 is loosely connected to the segment-shaped end 16 of the handle or lever 3 by a pin or rivet 20, which passes through the slot 17 of the handle or lever. The pierced bifurcated end 9 of the jaw 2 is pivotally connected to the segment shaped end 16 of the handle or lever 3 by a pin or rivet 21. Seating in the cut away ends of the jaws 1 and 2 are toothed or serrated plates 22, the rear face of one of said plates having an enlargement 23 adapted to fit in the recess 11 of the jaw 2. The plates 22 are retained in engagement with the jaws 1 and 2 by screws 24, secured in the threaded openings 6 and 12 of said jaws. In using the plates 22, I am enabled to remove and renew the same when they have become 95 worn, thus increasing the efficiency of my improved wrench.

In Fig. 2 of the drawing, I have illustrated a wrench in full lines as having its jaws closed, and to open the same it is necessary that one of the jaws be gripped or placed in engagement with an object. Assuming that this has been done, the handle or lever 3 is moved, and owing to the fact that the distance between the pivotal points of one jaw 105 is shorter than between the pivotal points of the other jaw, a movement of the handle or lever 3 to the right will tend to force the jaws rearwardly, the jaw 2 moving faster than the jaw 1, whereby the jaws will be thrown open, 110

when the limit of their movement is reached. A reverse movement of the handle or lever 3 will close the jaws. From this construction of my improved wrench it will be observed that when any strain or stress is brought to bear upon either one of the jaws the strain or stress is equalized between the segment shaped end of the handle or lever 3 and both of said jaws.

10 It is obvious that the plates 22 can be readily operated upon any flattened surfaces provided for gripping nuts or similar objects.

By arranging the slot 17 at an angle to the longitudinal plane of the handle 3 the jaws 15 are caused to move in the course indicated by the dotted lines in Fig. 2, the jaw 1 moving through a greater distance during the operation than the jaw 2 and thereby engaging the article between the operating faces and tightly compressing the same by the strong leverage produced by the angular direction in which the slot 17 extends. The manipulating of the handle 3 thus produces 20 a very strong wedging action upon the jaw

1 through its contact with the pin 20, and 25 thereby producing a very strong grip upon the article held between the jaws. This wedge like action is an important feature of the invention and adds very materially to its utility and efficiency.

30 What I claim and desire to secure by Letters Patent, is:—

A wrench comprising a handle provided with an enlarged end and having a segmental slot formed therein, jaws pivotally connected together at their centers and freely movable, one of the jaws pivoted to the enlarged end of the handle and a pin passing through the other jaw and segmental slot whereby the jaw obtains a gripping action throughout the 35 slot by the pin bearing against the wall of the slot.

40 In testimony whereof I affix my signature in the presence of two witnesses.

HARRY W. ALLISON.
